UNITED STATES PATENT OFFICE.

JOHN. D. SULLIVAN, OF SALT LAKE CITY, UTAH.

FIREPROOF WALL AND PARTITION.

No. 876,605.

Specification of Letters Patent.

Patented Jan. 14, 1908.

Application filed April 30, 1907. Serial No. 371,034.

To all whom it may concern:

Be it known that I, JOHN D. SULLIVAN, of Salt Lake City, in the county of Salt Lake and State of Utah, have invented certain new and useful Improvements in Fireproof Walls and Partitions; and I do hereby declare the following to be a full, clear, and exact description of the invention, such as will enable others skilled in the art to which it appertains to make and use the same.

The primary object of this invention is to so construct the blocks or sections composing a fireproof wall or partition as to render unnecessary the use of laths, studding, or grounds of any kind; and which may be used for either exterior or interior purposes. And a further object is to provide a fireproof wall or partition which will occupy but little space; which will require but one coat of plaster; which will be sound-proof; which will form conduits for pipes and wires; and to which the trim or finish may be directly secured.

The invention will be hereinafter fully set forth and particularly pointed out in the claims.

In the accompanying drawings, Figure 1 is a side elevation, with parts in dotted lines. Fig. 2 is a transverse sectional view on line 2—2, Fig. 1. Figs. 3 and 4 are opposite edge views, with portions of adjoining blocks broken away. Fig. 5 is a longitudinal sectional view on line 5—5, Fig. 3. Fig. 6 shows a corner block or section. Fig. 7 is a vertical longitudinal sectional view of a portion of a completed wall or partition.

Referring to the drawings, 1 designates a block in its entirety. It is formed with spaced apart sides 2, a central connecting web 3 and two end connecting webs 4, all being integral. The intervening hollow spaces 5 may be employed as conduits for pipes and wires, and being dead-air spaces serve as sound deadeners. In each end of the block, between the sides 2, is formed a groove 6, the faces of the webs 4 being slightly concaved. The opposite ends of these grooves are slightly flared or belled, as at 7, and the opposite ends of the web 3 are formed with recesses 8. The block is preferably composed of fibrous gypsum hard wall-plaster composition, and in each side 2 is a metallic re-inforcement 9, preferably wire-mesh.

In building up a wall or partition, the series of blocks composing each row are arranged end to end, the contiguous grooves 6

forming a space or chamber which is designed to be filled with a plastic binder, preferably fibrous plaster, the binder being poured in at the top. In this way the several blocks composing each row are secured together. The blocks of the next or superposed row are arranged to break-joint with the blocks of the lower row, the webs 3 being thereby caused to coincide with the plaster filled spaces or chambers. The recesses in the lower ends of webs 3 are trowel-filled with the binder, making thereby a slight joint between the rows. When the binder sets or hardens it forms a key by which several rows are secured together at top and bottom, and the blocks of each row are united at their meeting edges, forming a continuous bond for the entire wall or partition. In wall construction, the finishing coat of plaster is alone necessary, the first or rough coat not being required.

From what has been said the advantages of my invention will be apparent. The connecting webs 3 and 4 form solid piers extending from floor to ceiling, rendering the use of studding or grounds unnecessary, since the trim or finish may be nailed directly to the web-formed piers. Not only is the wall sound-proof, but the spaces 5 may be utilized as conduits. Each block may be made of any desired thickness and of any suitable length and height, and under ordinary conditions a wall thus formed occupies only about one-half the space of an ordinary lath and plaster wall.

I claim as my invention:

1. A wall or partition composed of superposed rows of blocks, each block having spaced-apart sides and webs connecting said sides at their centers and ends, vertical grooves being formed in each end of the block and recesses in the upper and lower ends of the central webs, and plastic binding material in said grooves and recesses, the end webs of the blocks of one row being located in line with the central webs of the blocks of the next adjacent row, the spaces between said sides and the central and end webs forming conduits.

2. A wall or partition composed of superposed rows of blocks, each block having spaced-apart sides and webs connecting said sides at their centers and ends, vertical grooves being formed in each end of the block and recesses in the upper and lower ends of the central webs, said grooves at

their ends being belled, and plastic binding material in said grooves, the belled ends thereof and said recesses, the end webs of the blocks of one row being located in line with the central webs of the blocks of the next adjacent row, the spaces between said sides and the central and end webs forming conduits.

3. The wall block herein-described consisting of two spaced-apart sides and webs formed integral with said sides at the centers and ends thereof, long narrow conduits being formed between said sides and closed at the ends by said webs; grooves being formed between said sides at the ends thereof and recesses in the opposite ends of the central web.

4. The herein-described block for walls or partitions composed of fireproof material and formed with spaced-apart sides, each side having metallic reinforcing therein, such block having webs connecting said sides at or near its ends and at a point intermediate said ends, the latter web having recesses in its opposite ends, and the end webs having grooves formed therein.

In testimony whereof, I have signed this specification in the presence of two subscribing witnesses.

JOHN D. SULLIVAN.
